UNITED STATES PATENT OFFICE.

FRANK A. BEARD, OF COLUMBUS, OHIO.

THEATRICAL DEVICE.

Application filed June 27, 1922. Serial No. 571,184.

To all whom it may concern:

Be it known that I, FRANK A. BEARD, a citizen of the United States of America, residing at Columbus, in the county of 5 Franklin and State of Ohio, have invented certain new and useful Improvements in Theatrical Devices, of which the following is a specification.

My present invention relates generally to 10 theatrical devices and more particularly to stage settings, especially those in the nature of optical illusions, my primary object being the provision of a stage setting by means of which an appearance is presented 15 as if the audience were viewing the scene from above.

A further object is the provision of a stage setting of the above type having normally concealed means allowing of the movement 20 of persons and articles thereon and permitting of movement thereof in certain respects without exposing the concealed means to the audience.

With these general objects in mind, further and more specific objects, as well as the resulting advantages of my invention, will be apparent from the following description, reference being made to the accompanying drawings, forming part of this 30 specification, and wherein,

Figure 1 is a sectional side view illustrating the practical application of the invention,

Figure 2 is a front elevation of my improved stage setting,

Figure 3 is an end view thereof,

Figure 4 is a partial horizontal section taken on line 4—4 of Figure 3,

Figure 5 is a vertical sectional view taken 40 on line 5—5 of Figure 2,

Figure 6 is a fragmentary rear elevation on an enlarged scale,

Figure 7 is an end view illustrating one use of the invention,

Figure 8 is a vertical sectional view illustrating another use,

Figure 9 is a sectional view taken on line 9—9 of Figure 10,

Figure 10 is a detail cross section on line 50 10—10 of Figure 9,

Figure 11 is a similar view with the parts slightly shifted,

Figure 12 is a top plan view of the shoe-carried holding lug,

55 Figure 13 is a top plan view of the lug holding socket.

Referring now to these figures and particularly to Figures 1 to 5 inclusive, I have shown in Figure 1 portions of a stage 15 on which my improved setting is movable by virtue of its frame 16 mounted on rollers or casters 17 and supporting an upwardly and rearwardly inclined panel 18 whose inclination approximates a right angle to the line of vision of the audience in front of the stage 15. The panel 18 forms the main front of the setting and may be held by rear braces 19 rising from the frame 16, the latter of which also supports a trough 20 below and along the lower edge of the panel 18 and a suitably decorated end panel 21. This trough has a discharge spout 22 at one end which may be connected to a suitable flexible or other discharge pipe 23 as seen in Figure 2.

Spray pipes 24 and 25 extend along the upper and lower edges of the main panel 18 and the end panel 21 and are provided therewith with spaced inclined discharge nozzles so disposed as to discharge water in a film over the panels. These spray pipes 24 and 25 lead from a supply pipe 26, the latter of which may include a heater 27, and said spray pipes are preferably provided with individual valves 28 and 29 so that they may be controlled to deliver just sufficient fluid through the nozzles 24^a and 25^a to film the panels, or sufficient to not only film the panel, but cause ripples across the same. In its passage over the face of the panels, the film of water is intended to jump certain gaps in the form of spaced openings 30 and 31 in the main panel, which are connected by a conduit 32 along the rear surface of the panel, the latter of which may have a central rear opening 33 shown in dotted lines in Figure 2.

The panel 18 may have a slot 34 extending between the openings 30 and 31 through which a rope or other line may pass and water is preferably sprayed along the sides of the openings to join the surface film, through nozzle apertures 35 in Figure 5 fed by pipes 36 and 37 having valves 38 and 39 and leading from the pipe 24.

Below the opening 30 panel 18 has a third opening 40, see Figure 5, through which an irregularly shaped protuberance 41 is preferably adjustable so as to project more or less through the film of water and representative of a rock. This protuberance preferably embodies a second adjustable

protuberance 42 supported therein and adjustable therewith and in respect thereto. Each protuberance has a rack 43 engaged by a gear 44, these gears being mounted on shafts 45 at the rear of the panel 18, each shaft having a crank 46. The forward surfaces of these rock-like protuberances have sockets 47 shown more particularly in Figures 9 to 13, which are for a purpose to be 10 presently described and may also be formed in slides or other supporting devices as for instance a boat 48 shown in Figure 8 and movable across the front face of the panel, any suitable supporting devices being utilized as indicated at 49 in this figure.

Along the lower edge of the panels are preferably supported a series of rollers 50 on which a panel 51 forming an inspection front may be shifted in front of and away 20 from the main panel 18, this inspection front when across the panel 18 completely covering the main panels, its openings and parts so as to conceal the same during inspection of the setting before or after its use. When 25 the film of water is discharged over the surface it is obvious this panel or inspection front 51 may be shifted laterally and withdrawn without being seen.

The panel 31 may be a mirror and the surface decoration as well as the structure of the panel 18 will of course depend upon the scene it is desired to show, its position and arrangement making it appear to the audience that they are looking down upon persons or articles either stationary or in movement on the panel.

To support persons or articles therein, lugs 52 as in Figures 9 to 13 are provided to cooperate with the sockets 47 before referred to, and in the case of persons, these lugs 52 are fastened to their shoes 53 so that by shifting the feet the lugs can be disengaged and thus in the instance of the diving girl of Figure 1, she may go into the opening 30, through the conduit 32 and appear again at the opening 31.

Furthermore by reversing the sockets 47 and lugs 52 in pairs as shown, the performer may first disengage the front lugs 50 and pass a rope and the like as in Figure 7 under the arch of the foot and then reengage the front lugs and disengage the rear lugs so that the rope may be shifted completely beneath the feet. The inner ends of the sockets 47 may be covered by doors 54 and, if so desired locking means indicated at 55 in Figure 10 may be employed to prevent displacement of the lugs.

In use on a stage 15, the setting as a whole 60 is first wheeled to place and a curtain 56 is preferably dropped over its upper edge. A second curtain or pad 57 may be used to cover the lower edge and to prevent injury to the performer should the latter slip. In 65 the first instance the main panel 18 will be

covered and concealed by the inspection panel 51, the latter being shifted from in front of the main panel after the film of water flows thereover, in order that its removal may not be observed. It is obvious 70 an interesting and mystifying illusion will thus be presented, which will be entertaining and capable of use in various scenic displays and with a variety of purposes.

I claim:

1. A stage setting of the character described including a portable supporting frame, a scenic panel held in an upwardly and rearwardly inclined position in the frame, means for discharging a film of water downwardly over said panel, and a second panel shiftable laterally across the first panel within and concealed by said water film.

2. A stage setting of the character described including a wheeled support, a main panel disposed in an inclined position in the support, means for discharging a film of water over the forward face of the said panel and a covering panel for the main panel 90 shiftable from the latter within the water film.

3. A stage setting of the character described including a wheeled supporting frame, an upwardly and rearwardly inclined main scenic panel in the frame, a trough supported by the frame along the lower edge of said panel, means along the upper edge of said panel for discharging a film of water downwardly thereover, and an inspection panel normally covering the main panel and shiftable therefrom in the film of water.

4. A stage setting of the character described including a wheeled supporting frame, an upwardly and rearwardly inclined main scenic panel in the frame, a trough supported by the frame along the lower edge of said panel, means along the upper edge of said panel for discharging a film of water downwardly thereover, and an inspection panel normally covering the main panel and shiftable therefrom in the film of water, said main panel having openings therein and means for discharging water through said openings into the water film.

5. A stage setting of the character described including an upwardly and rearwardly inclined main panel, an inspection panel shiftable across the front face of the main panel and normally covering the same, and means for delivering a film of water over said panels under cover of which film the inspection panel may be withdrawn.

6. A stage setting of the character described including an upwardly and rearwardly inclined main panel, an inspection panel shiftable across the front face of the main panel and normally covering the same, and means for delivering a film of water

over said panels under cover of which film the inspection panel may be withdrawn, said inspection panel having a mirror surface and being imperforate.

5 7. A stage setting of the character described including an upwardly and rearwardly inclined main panel, an inspection panel shiftable across the front face of the main panel and normally covering the same, 10 and means for delivering a film of water over said panels under cover of which film the inspection panel may be withdrawn, said main panel having openings across which the water film flows when the inspection 15 panel is withdrawn.

8. A stage setting of the character described including an upwardly and rearwardly inclined main panel, an inspection panel shiftable across the front face of the 20 main panel and normally covering the same, and means for delivering a film of water over said panels under cover of which film the inspection panel may be withdrawn, said main panel having openings across 25 which the water film flows when the inspection panel is withdrawn, and also having a rear conduit connecting said openings.

9. A stage setting of the character described including an upwardly and rearwardly inclined main panel, an inspection 30 panel shiftable across the front face of the

main panel and normally covering the same, and means for delivering a film of water over said panels under cover of which film the inspection panel may be withdrawn, said 35 main panel having means for supporting a performer thereon.

10. A stage setting of the character described including an upwardly and rearwardly inclined main panel, an inspection 40 panel shiftable across the front face of the main panel and normally covering the same, and means for delivering a film of water over said panels under cover of which film the inspection panel may be withdrawn, and 45 means for supporting a performer on the main panel.

11. A stage setting of the character described including an upwardly and rearwardly inclined main panel, an inspection 50 panel shiftable across the front face of the main panel and normally covering the same, and means for delivering a film of water over said panels under cover of which film the inspection panel may be withdrawn, and 55 means for supporting a performer on the main panel, including scenic means adjustable through the scenic panel.

In testimony whereof I have affixed my signature.

FRANK A. BEARD.
